A. F. HAMMOND, OF HOUSTON, OHIO.

Letters Patent No. 62,955, dated March 19, 1867.

IMPROVEMENT IN GARDEN SYRINGES.

The Schedule referred to in these Letters Patent and making part of the same.

TO ALL WHOM IT MAY CONCERN:

Be it known that I, A. F. HAMMOND, of Houston, in the county of Shelby, and State of Ohio, have invented a new and improved Device for Throwing Water; and I do hereby declare the following to be a full, clear, and exact description of the same, sufficient to enable one skilled in the art to which the invention appertains to make use of it, reference being had to the accompanying drawings, which form a part of this specification, and in which my invention is represented by a longitudinal sectional view.

The water-chamber of this instrument is emptied by means of a piston operated by a rack and a pinion upon a crank-shaft. The water is ejected in a stream through a nozzle.

The invention consists in the arrangement of the parts, whereby a considerable force is brought to bear upon the piston with one hand, while the other hand supports the apparatus.

The instrument is designed to contain as much as can be conveniently handled by one person, say from one to four gallons, and being directed by one hand, and supported against the person if necessary, the handle *a* is rotated with the right hand, the cogs *b* of the pinion engaging those of the rack *c*, and driving the piston *d*, in the cylinder *e*, forcibly ejecting the water at the nozzle *f*. The rack *c* moves in ways or guides in the frame *g*, in which also the shaft *h* of the crank has its bearing. The springs *h'* of the piston give it a certain elasticity, and by compression during the operation they will continue to deliver water at the nozzle for awhile after the crank ceases to move. The nozzle *f* is so socketed in the delivering end of the cylinder that when pressure is brought upon the piston the water holds the truncated conical nozzle-piece firmly against its seat, but when the end of the empty cylinder is plunged into a tub or bucket of water, the nozzle retreats so as to permit the entrance of water through the annular space between the conical base of the nozzle and its seat. This expedites materially the filling of the chamber. The apparatus is useful in many ways: In directing a stream against a distant or inaccessible part of a roof which is on fire, or in syringing trees or shrubs infested by insects. If desired, a reservoir for the automatic supply of water to the chamber may be had, consisting of a water-tight bag carried on or suspended to the shoulder, and communicating by a flexible tube with the chamber through a valved opening in a plate behind the piston.

Having described my invention, what I claim therein as new, and desire to secure by Letters Patent, is—

1. The arrangement of the cylinder *e*, spring-piston *d*, operated by rack and pinion, substantially as described and represented.

2. In combination with the subject-matter of the first claim, I claim the movable nozzle operating as described.

To the above specification of my improved device for throwing water, I have signed my hand this twenty-ninth day of August, 1866.

A. F. HAMMOND.
